INVENTOR.

GUSTAVE A. TROST
BY *G. M. Johnson*
ATTORNEY

UNITED STATES PATENT OFFICE

GUSTAVE A. TROST, OF SAN FRANCISCO, CALIFORNIA

CARTON

Application filed February 11, 1930. Serial No. 427,516.

My present invention relates to cartons, and more particularly to a carton having means whereby it may be readily opened to provide a so-called pouring outlet.

5 An object of my invention is to provide a simple, cheap and practical type of carton which can be readily opened by a simple hand operation without resorting to any special knife or tool for the purpose.

10 Another object of my invention is to provide a novel arrangement and design of flaps for a carton which, when folded, will provide a ready means of access to the contents of the carton with a minimum of inconvenience.

15 In the art to which my invention pertains there are a great many cartons having the so-called pouring outlets. These cartons are generally used for the distribution of salt, 20 sugar, and other granular commodities. So far as I am aware, all the prior art cartons of this type require some special form of spout or closure device which is made separately and attached to the carton blank, 25 and for this reason the cartons become more or less complicated and also expensive to manufacture.

It is therefore a further object of my present invention to provide a carton upon which 30 there is formed integral with the blank suitable flaps having cooperating parts which provide a new and novel means whereby the carton may be readily opened to permit a pouring of its contents. This object is accomplished by the provision of an aperture in one of the flaps, a freely hinged tongue portion on another of the flaps which is adapted to cover the above referred to aperture, and a scored portion upon another 35 of said flaps which is positioned directly above the tongue portion and which serves to hold said tongue portion in a position where said aperture is closed, and because of its scored 40 condition, permits a relatively easy lifting

of said tongue to expose the pouring aperture.

For a better understanding of my invention, reference should be had to the accompanying drawing wherein I have shown, by 50 way of illustration and not of limitation, a preferred embodiment thereof.

In the drawing wherein like numerals refer to like parts throughout the several views:

Fig. 1—is a fragmentary perspective view 55 of the end of a carton showing the closing flaps extended.

Fig. 2—is a view similar to Fig. 1 showing two of the flaps folded in.

Fig. 3—is a view similar to Fig. 2 showing three of the flaps folded into their carton closing position.

Fig. 4—is a view similar to Fig. 3 showing all of the flaps folded into the carton as when the carton is sealed, and

60 Fig. 5—is a partial view in development showing the blank extended and the relative positions of the co-operating parts upon the flaps which provide the pouring opening.

65 By referring to the drawing it will be seen that my improved carton blank comprises a body portion, designated by the numeral 10, having suitable flaps formed at each end which provide a closure when the carton is assembled. On at least one end of 70 the blank, and preferably the top end, the closure flaps are arranged as follows: Along the narrow sides of the carton I provide oppositely disposed flaps 11 and 12 which extend to the middle of the carton and along the flat sides of the carton I provide similarly disposed flaps 13 and 14 which are adapted to be folded in over-lapping relation over the flaps 11 and 12 so that when the carton is glued in the usual way the end will be sealed.

75 80 85 90 The above arrangement, it will be understood, is substantially standard practice. It is at this point where I depart from the standard practice and embody in the carton blank

features which I consider to be new, novel and patentable.

Having a blank of the above general outline, I next provide one of the narrow flaps, 5 as shown in the drawing, the flap 12 with a suitable opening 15. This opening 15 is illustrated as disposed centrally of the flap 12. I next form a free hinged tongue portion 16 upon the flap 13 in such a manner 10 that when the flap 13 is folded over the flaps 11 and 12 the opening 15 will be covered and closed by the tongue 16. As a final step I also outline a portion 17 which may be readily torn away by scoring the flap 14 as shown. 15 This outlined portion 17 is so disposed that it will over-lie the tongue 16 and hold it in a sealing position over the opening 15. In forming the tongue 16 upon the flap 13 I cut away a small portion in the side of the flap 20 12 and thus produce a tongue of such a length that it will project outwardly slightly beyond the outline of the carton. In practice the projection of the tongue 16 beyond the edge of the carton need not exceed one-quarter inch. 25

This latter feature is very well illustrated in Fig. 5 of the drawing wherein the tongue 16 is shown as having its extending end cut out of the left-hand side of the flap 12. 30 While reference is being had to Fig. 5 of the drawing, attention is directed to the provision of a gluing portion 18 which cooperates with an adjacent side of the carton as a means of sealing the carton lengthwise. 35 After the carton has been formed in the usual manner it may be placed in a filling machine with the flaps 11 and 12 and 13 and 14 in the position illustrated in Fig. 1. After the carton has been filled, the flaps 11 and 40 12 may then be folded down, as illustrated in Fig. 2. The operator will then apply the glue to the flaps in any desired manner and may then fold the flap 13 with its tongue 16 down over the flaps 11 and 12, as shown in 45 Fig. 3, and as a final operation the flap 14 can then be folded down over the flap 13 into its position. At this point pressure upon the flaps will finally seal the carton.

Should it be desired now to pour the contents of the carton, it will only be necessary to grasp the projecting end of the tongue 16 and pull it upwardly against the scored portion 17 which will readily yield or tear free from flap 14 and permit an exposure of the 55 opening 15 in the flap 12 through which the contents of the carton may be readily poured.

While I have for the sake of clearness and in order to disclose my invention so that the same can be readily understood, described in 60 general terms and illustrated specific devices and arrangements, I desire to have it understood that this invention is not limited to the specific form disclosed but may be embodied in other ways that will suggest themselves, 65 in view of this broad disclosure, to persons

skilled in the art. It is believed that this invention is broadly new and it is desired to claim it as such so that all such changes as come within the scope of the appended claims are to be considered as part of this 70 invention.

Having thus described my invention, what I claim and desire to secure by Letters Patent is:

1. In a carton having the usual over-lapping flaps for closing the end thereof, the combination of a flap having an opening therethrough, a second flap having a portion disposed over said opening and cut to form a hinged tongue, and a third flap having a 80 scored portion disposed over said tongue adapted to be easily torn free when said tongue on said second flap is pulled to thereby expose the opening in said first flap and provide a pouring opening in the carton. 85

2. In a carton having the usual over-lapping flaps for closing the end thereof, the combination of a flap having an opening therethrough, a second flap having a portion cut free to form a hinged tongue, and a third flap having a portion scored and adapted to be easily torn free, said flaps being disposed one over the other, whereby when said tongue on said second flap is pulled said scored portion on said third flap will be torn away and 90 the opening in said first flap exposed. 95

3. A blank for carton and the like comprising a body portion having a plurality of foldable flaps at the end thereof adapted to over-lap and close the carton when assembled, one of said flaps having a hinged tongue member formed thereupon adapted to project beyond the limit of the carton when the same is assembled, and a second flap having a scored portion disposed over said tongue member adapted to hold the tongue in a carton closing position until the tongue is pulled to open the carton substantially as described. 100

4. A blank for pouring cartons of the character described, comprising a single flat sheet of material having three adjacent flaps which are adapted to overlie each other when folded and provide a pouring opening through the end of the carton formed, the inner one of said flaps having an opening 15 therethrough, another of said flaps having a scored portion 17 extending into the side thereof and the other of said flaps having a tongue portion 16 which extends across the fold line of the blank so that when the latter is folded the tongue 16 will be disposed over the opening 15 and under the scored portion 17 and extend beyond the edge of the carton. 110

5. A blank for cartons and the like, comprising a body portion having a plurality of foldable flaps at one end thereof adapted to overlap and close the carton when assembled, one of said flaps having a hinged tongue member formed thereupon which extends over one of the fold lines of the blank when 120 125 130

flat and is adapted to project beyond the edge of the carton when the same is folded and assembled.

6. A blank for cartons and the like, comprising a body portion having a plurality of foldable flaps at one end thereof adapted to overlap and close the carton when assembled, one of said flaps having a hinged tongue member formed upon one of its sides, said tongue member being cut across one of the fold lines of the blank from the adjacent sides of two of the flaps when the blank is flat, whereby its end will project outwardly from the carton when closed.
